(57) **CLAIM**

I claim the ornamental design for a dual material pet treat, as shown and described.

DESCRIPTION

FIG. 1.1 is a perspective view of a dual material pet treat showing my new design;

FIG. 1.2 is a top view thereof;

FIG. 1.3 is a rear view thereof;

FIG. 1.4 is a front view thereof;

FIG. 1.5 is a back view thereof;

FIG. 1.6 is a left side view thereof; and

FIG. 1.7 is a right side view thereof.

The broken lines in the drawings depict portions of the dual material pet treat that form no part of the claimed design.
